Application May 2, 1936, Serial No. 77,468
 In Belgium May 21, 1935

7 Claims. (Cl. 237—9)

My invention relates to systems of heating by vacuum. As is well known, the system of heating by vacuum utilises steam, the pressure of which is lower than that of the atmosphere. This steam removed from the boiler by means of a pump is distributed in radiators or other apparatus of a heating installation where it is condensed.

The water of condensation afterwards returns to the boiler to be evaporated again.

Two forms of essential construction of this heating system are known:

1. The fixed vacuum system in which steam at constant temperature is employed.

15 2. The variable vacuum system in which steam at variable temperature is employed.

In the system mentioned under (1), a relief valve is provided on the departure pipe-line which valve is adjusted for a pressure lower than that of the atmosphere, and in order for the relief valve to open and allow steam to pass it is necessary for a pump to produce in the heating network a vacuum corresponding to the regulating pressure of the expansion device.

25 The fixed vacuum may be regulated for any pressure. It may be carried out with any steam temperatures between 55° and 100° C., but the temperature fixed by the original regulation cannot be varied.

30 When it is a matter of buildings with regular heating during the whole of a winter, it will be seen that the fixity of the temperature of the steam does not enable one to obtain an advantageous adjustment corresponding to the variations

35 of the external temperature and permitting comfort and maximum fuel economy to be secured.

That is why installations have been constructed which operate under variable vacuum and distribute the steam at a variable temperature to the

40 radiators.

In these systems operating with variable steam temperature the pipe-line carries variable quantities of steam at different densities due to the variations of temperature. The work of the

45 vacuum pump consists in ensuring the circulation of this steam while maintaining in the entire network the necessary vacuum for obtaining the desired steam temperature.

In a network of pipe-lines of vacuum heating,

50 two very distinct portions can be distinguished:

1. The pipe-lines conducting the steam to the heating appliances.

2. The pipe-lines which return the condensed water to the boilers, and as these two portions

55 are separated by radiators, it will be appreciated

that the steam leaving the principal header of the boiler to pass to the radiators is subject to a loss of head which is variable according to the absolute pressure prevailing in the network, which absolute pressure determines the quantity 5 of steam to be transported into the heating appliance.

The object of this invention is to produce automatically a vacuum corresponding to the quantity 10 of steam necessary for the heating network, this quantity of expanded steam being always proportional to the temperature prevailing in the rooms to be heated.

With a view to accomplishing this object, the invention comprises substantially the utilisation 15 of a vacuum and steam relief valve or a combustion regulator composed of flexible diaphragms fixed to a system of levers and counterweights moving simultaneously so as to maintain differences of pressure proportional to the resistances 20 to be overcome.

The systems of levers and counterweights are constructed so that the difference of the absolute pressures prevailing on the vacuum regulator and expansion device or the combustion regulator is 25 always equal to the losses in head caused by the steam in the distribution pipe-lines together with the resistances of the cocks and drain-cocks of the radiators.

It should be remarked, however, that in such a 30 system it is indispensable that the vacuum produced does not exceed the losses in head to be overcome for ensuring the movement of this steam.

In fact, if the partial vacuum produced is 35 greater than the losses of head the excess work of the pump evaporates the water in contact with the saturated steam.

In this case, the vacuum pump functions without stoppages to produce steam from the critical 40 point at which the partial vacuum has exceeded the work necessary for overcoming the losses of head. It follows from this fact that the fall in vacuum is impossible.

It will thus be understood that it is important 45 to have an automatic regulation such that there corresponds to each quantity of steam sent into the network:

1. The vacuum necessary for obtaining steam 50 adapted to ensure without excess the temperature of the rooms.

2. The difference in vacuum necessary, and without excess, for overcoming at any instant the sum of the losses in head.

The resistances which have to be taken into consideration are the following:

1. The loss in head during flow in the pipe-line from the regulator to the cock of the radiator (R1).

2. The resistance to the passage of the steam through the cock (R2).

3. The resistance to the passage of the condensation water through the drain-cock (R3).

10 When an installation is completed the invariable resistances are the losses in the lines (R1) and those of the drain-cock (R3) adjusted at the works. The magnitude of the losses (R1) may vary appreciably from one circuit to the other in

15 view of the material impossibility of ensuring losses of head which are equal in all the circuits.

According to the invention, in order to regularise the whole and to obtain an exact equal distribution of the pressures the resistances R2 are

20 modified according to requirements so that the sum of the resistances $R1 + R2$ is quite constant for all the circuits.

Steam heating systems are known in which a differential pressure controller is connected between the supply and return sides of the system, the controller governing the operation of the exhausting means so as to maintain a substantially constant and predetermined difference in pressure between the supply and exhaust sides of the radiator, irrespective of the absolute steam pressure in the radiator.

In this system, a pressure reducing device is automatically controlled by an electric device actuated by a thermostat situated in one of the rooms being heated. Changes in the temperature of the room give rise through the pressure reducing valve to variations in the supply, the pressure and the temperature of the steam.

A vacuum controller produces the regulation by maintaining a constant difference of pressure between the vacuum produced by the pump and the absolute pressure obtained at the pressure reducing valve under the action of the thermostat.

The automatic pressure reducing device and the vacuum controller can only work correctly if each radiator is provided at its outlet with a thermostatic steam trap which allows the exhaust of the condensate in the return pipe only when the condensate is at a temperature which is lower than the vaporizing temperature corresponding to the pressure of the vacuum produced by the pump.

As soon as the steam reaches the thermostatic diaphragm of the trap, the latter expands and obturates the passage through which the steam escapes in the condensed form (i. e., as water). As the water does not escape into the return line, it accumulates around the diaphragm and in the radiator. When the temperature of the water has been lowered sufficiently, the diaphragm contracts and permits the flow of the condensate. When steam is again received on the diaphragm, the latter expands and the passage again closes.

In this system it has been suggested to provide a single exhausting mechanism comprising a plurality of vacuum producing elements associated respectively with a plurality of radiating systems with means for placing each vacuum producing element into and out of operation independently, the said means consisting in a diaphragm operated valve which is responsive to change in the differential pressure between the supply and return sides of the space exhausted by the particular element.

75 In those known systems, there exists a vacuum

difference which is constant whatever may be the pressure and the temperature of the steam. The consequence is that an increasing supply of steam is obtained, when the temperature falls. In the present invention, on the contrary, the controller acts in such a manner that the difference of pressure is always proportional to the resistances to be overcome so that the vacuum difference diminishes when the quantity of steam diminishes and there exists no steam in excess.

The invention likewise relates to a construction of cocks intended to be utilised in the heating system (according to the invention) and rendering possible the adjustment of the said resistance R2, and also to a type of drain-cock adapted for use in this system.

The accompanying drawings show how the invention may be carried into practice:

Figure 1 shows a general diagram of a heating installation according to the invention;

Figure 2 is a sectional view of an expansion device for regulating the vacuum and the temperature of the rooms;

Figure 3 shows an installation in which a regulator is employed for the vacuum, the combustion and the temperature of the rooms;

Figure 4 shows a cock adapted to be placed on a radiator employed in a heating system according to the invention and of the type of that shown in Figure 5;

Figures 6, 7 and 8 are detail views;

Figure 9 shows a type of drain-cock to be fixed on a radiator of the type shown in Figure 5;

Figure 10 shows a cock which is provided with an air-escape device and intended for radiators fed by a single pipe conducting the steam and returning the water as shown in Figure 11;

Figure 12 is a view in detail;

Fig. 13 is a rear view of the vapor tension thermometer.

Referring to the drawings (Figures 1 to 3), 1 denotes the boiler and 2 the principal steam-manifold and 3 is a secondary distribution manifold to which are connected conduits C1—C2—C3 . . . c1, c2, c3, etc . . . terminating at the heating apparatus, for example radiators 4. Leaving the heating apparatus 4 are return conduits R, r1, r2, r3, etc . . . which terminate at a reservoir 5 for the condensed water. 6 denotes the drain-cocks and 7 the cocks of the radiators, 8 a siphon drain and 9 a general air vent.

On the conduit 3, is a pressure reducing apparatus for regulating the vacuum and the temperature of the room, which apparatus is denoted by A in Figure 1 and is shown in a detailed manner in Figure 2.

This apparatus comprises in the first place a chest 10 which is fixed to the manifold 3 and which comprises in the lower portion a diaphragm 11 clamped between a flange 12 on the said chest and a lid 13. Fixed to this diaphragm 11 is a rod 14 to which is connected a valve 15 controlling the passage of the steam. But even when the said passage is closed there remains an orifice 16 which allows a certain flow of steam depending upon the magnitude of the installation.

The device also comprises two orifices 60 and 61 of equal dimensions and adapted to be closed by pistons 62 and 63 assembled by a system of fins 64 for guiding. The whole is mounted on the rod 14.

In the solid line position, the pistons 62, 63 close the orifices 60 and 61. Under the influence of the action of the pressure on the diaphragm, the pistons move vertically and finally occupy

the extreme positions 62¹ and 63¹, thus giving passage to the steam which expands more or less in the space B according to the positions of the pistons which also depend upon the pressures exerted on the diaphragm according to the positions of the weights 31 and 38 controlled by the regulating system through the medium of levers.

Moreover, a rod 17 likewise fixed to the manifold 3 serves to support a chest 18 formed in two parts which clamp between them a diaphragm 19. The space 20 situated above the said diaphragm is connected by a pipe 21 to a vacuum pump 22 which likewise exerts its action in all the pipe-lines through the medium of a conduit 15 connected to the reservoir 5 and provided with an indicator 24 for the vacuum and temperature.

Fixed to the diaphragm 11 of the relief valve is a link 25 which is connected to a lever 26 adapted to oscillate about a pin 27 fixed to a lug 28 on the lid 13 and which lever 26 is provided with a slot 29 in which is a pin 30 supporting a weight 31. The pin of the weight is connected by a rod 39 to the lever 40 which is adapted to oscillate about a pin 41 and which can 25 actuate simultaneously the counterweights 31 and 38.

A similar arrangement is provided for the vacuum-regulating diaphragm, to which is fixed a link 32 which is connected to a lever 33 which 30 pivots about a pin 34 fixed to a lug 35 and comprises a slot 36 provided with a pin 37 for the suspension of a weight 38. The pin of the weight is connected by a link 47 to an arm of the lever 40 just referred to which is adapted to pivot about a pin 41. The said lever 40 is provided with an extension 42 adapted to be fixed in predetermined positions by a pin entering the holes 43 of a sector 44. The arm 40 is provided with a counterweight 46 at the end of its base 45.

40 Fixed to the lever 33 is a rod 48 acting on the electric circuit of a circuit-breaker 49 of known type adapted to stop the motor of the pump 22.

The operation is as follows:

The system being cold and the heating boiler 45 not lit, if the pump 22 is put into operation, vacuum is produced in the whole of the heating network, both in the return pipe-lines and in the steam pipe-lines.

The vacuum pump 22 exerts its action on the 50 diaphragm 19 through pipe 21 and on the diaphragm 11 through the pipe 23, reservoir 5 and the return pipes. When the vacuum attains the necessary intensity for balancing the weight 38, the lever 33 is raised and by means of the rod 48 breaks the electric circuit of the circuit-breaker 49 which stops the motor of the pump. Furthermore, the diaphragm 11 of the reducing 55 valve is likewise raised under the influence of the vacuum, and keeps open the balanced valve system which has to give passage to the steam.

60 As will be understood, by operating the lever 40 it is possible to move the weights 31 and 38, the controls of which are connected together, by virtue of the two links 39 and 47, and it is possible to increase or diminish the vacuum at will.

When the system operates under vacuum by the working of the pump but without steam being sent into the plant, so that the vacuum extends in a regular manner and with constant 70 absolute pressure in the plant, the pressures are equal at the vacuum regulator and at the reducing valve.

Considering now the normal operation, the steam from the boiler 1 passes through the fixed orifice 16 and the balance valve 15 of the re-

ducing valve expands under the influence of the vacuum and fills the entire steam network. Its absolute pressure is exerted on the diaphragm 11 and due to its action the quantity of steam passing the relief-valve is proportional to the intensity of the vacuum prevailing in the system.

The systems of levers and counterweights 29—31 and 33—38 are designed so that the difference in the absolute pressures prevailing on the diaphragms 11 and 19 is always equal to the losses 10 in head caused by the steam in the distribution pipe-lines, together with the resistances of the cocks and drain cocks of the radiators, as will herein after be more fully explained.

For that purpose the path through which each counterweight travels with respect to the path of the other counterweight varies in proportion to the drop in vacuum. The difference at the commencement of the movement, when the steam temperature is highest is greater than at the 20 end when the temperature is lowest.

The following example shows in detail the operation of this part of the apparatus.

The lever 40 being pivoted at 41 can act as 25 explained on the weights 31 and 38.

If it is remembered that the paths of the weights 31 and 38 are different, when the lever 40 is displaced, as the pivoting points 65 and 66 are situated at distances which are different from the pivoting point 41, it will be obvious that the 30 paths followed by the weights 31 and 38 are quite different. If the centre 66 is displaced, either by putting it closer or farther from the centre 41, it is possible to vary the ratio of the paths followed by the weights. During the movement 35 of the lever 40 the pivoting points 65 and 66 cause the weights 31 and 38 to travel through different parts corresponding to their distance from the centre 41. In other words, the entire distance moved by weight 38 is less than that moved by 40 weight 31. Moreover, as the weights progress toward the right the effective force of weight 38 on its lever 36 is less and less than that of weight 31 on its lever 26.

At the start, the weight 31 is slightly to the 45 left of the pin 27 and the weight 38 to the right of the pin 34.

There is produced a difference in pressure exerted by the weights on the diaphragms. This difference corresponds to the loss in head produced by the circulation of the steam at its highest temperature, that is to say, about 100° C. It is to be noted, however, that weight 31 does not exert a pressure on diaphragm 11 when said weight is at the left of the pin 27.

When the weights 31 and 38 are at the opposite end, this difference in initial pressure is reduced appreciably in order to make it correspond to the new loss in head produced by the steam at its lowest temperature that is to say about 60° C. 60 This latter loss in head is much lower than the initial loss due to the smaller flow of steam and the diminution of its specific gravity.

In addition, it is possible to modify on adjustment and according to requirement the size of the 65 weights 31 and 38 by the addition or removal of metal plates with the object of increasing or diminishing in the first place the necessary difference in the initial absolute pressure and secondly the ratio of this difference in the initial 70 pressure when the temperature of the steam is highest to the final difference corresponding to the lowest temperature.

In all the successive positions occupied by the weights 31 and 38 these differences are always 75

proportional to the losses in head due to the flow of steam for the flows corresponding to the steam temperatures in the limits of about 60° C. and 100° C.

- 5 Under the influence of the action of the vacuum pump, the weight 38 is gradually raised and the pivot of the rod controlling the circuit-breaker is thus caused to occupy successively positions which eventually cause the interruption of the electric circuit and the stopping of the motor of the pump. The inverse phenomenon is produced when the vacuum has become insufficient. As the weight 38 rises, due to the fixity of the centre 65, it also approaches the pin 34 which diminishes its action and facilitates the rapid control of the circuit-breaker.

When the vacuum is weak and the steam is at its highest temperature, the weight of steam carried is a maximum, and the differences in the absolute pressures on the diaphragms 11 and 19 are also a maximum. Conversely, when the vacuum is high and the temperature of the steam is low, the weight of steam carried is a minimum and the differences in the absolute pressures on the diaphragms 11 and 19 are also a minimum.

When the vacuum is low at the exit of the steam from the steam pressure reducing apparatus for instance with an absolute pressure of 0.950 kgr. the weight of steam which is carried may be supposed to be of 2000 kgr. per hour. The differences in the absolute pressures on the diaphragms 11 and 19 are also a maximum and can be regulated to a difference of 0.150 kgr. When the degree of vacuum is important and the corresponding absolute pressure is of 0.200 kgr., the weight of steam which is carried can be regulated by means of the apparatus within the limits of 400 to 800 kgr. per hour.

This combination of levers is therefore such that in all points of the position of the weights 31 and 38 along the levers, the differences in absolute pressures on the diaphragms 11 and 19 correspond exactly to the losses in head due to the flow of steam in the distribution network.

45 When this difference exceeds by a very small quantity the said loss of head, the lever 33 is raised and by means of the rod 48 breaks the electric circuit of the circuit-breaker 49 and stops the motor of the pump; when the vacuum diminishes and the difference in absolute pressure on the diaphragms 11 and 19 is a little less than that necessary, the weight 38 actuates the lever 33 and by means of the rod 48 starts up the motor again for the time necessary to re-establish the required difference.

In order to effect the regulation of the temperature of the rooms, the pressure of the water from a reservoir 50 (Figure 1) is utilised, which water may be carried by a pipe 51 to a chest 52 containing a diaphragm 53 on which the water acts. The water of the pipe-line 51 (Figure 2) coming from the reservoir 50 passes through a capillary diaphragm 54, exerts its pressure on the diaphragm 53, leaves by a tube 55, passes through a thermometer dial 56 and returns through the conduit 57 to the pump reservoir 22.

To summarize, the plant is composed of the following main elements:

- I. The temperature regulating device.
- II. The vacuum regulating device.
- III. The steam expansion regulating device.

The temperature regulating device is composed of a casing containing the diaphragm 53. To one face of the latter is connected the lever 59 which actuates lever 40 adapted to oscillate around a

fixed pivot 41. In the chamber formed between the casing and the other face of the diaphragm open two pipes: 51 and 55.

A fluid coming from the reservoir 50 passes through the pipe 51 into the said chamber and exerts pressure on the diaphragm 53, said fluid leaving the chamber by the pipe 55, which communicates with a thermometer which is situated in the room the temperature of which is to be regulated. As hereinbefore explained, the vapour tension obturates more or less the passage of the liquid under pressure.

The vacuum regulating device

One face of the diaphragm 19 actuates, through the intermediary of link 32 the system of levers 33—36 adapted to oscillate around a fixed point 34.

The other face of the diaphragm is in communication through the pipe 21 with the vacuum pump and the return pipe of the plant.

The system of levers 33—36 includes the weight 38 which is adapted to be displaced along the entire length of the branch 36 of lever 33.

If the surface of the diaphragm is equal to S_n cm^2 and if the weight 38 suspended at the centre of the diaphragm is of P kgr. the diaphragm begins to be tilted progressively when the vacuum pump has produced a depression equal to

$$\frac{P}{S_n}$$

When the degree of vacuum has become slightly greater than

$$\frac{P}{S_n}$$

and when it has reached a quantity of

$$\frac{P}{S_n} + E$$

the rod 48 will stop the motor by means of the circuit breaker 49. When the vacuum has diminished by E , the system of levers begins a movement in a reverse direction before it reaches an equilibrium state of

$$\frac{P}{S_n}$$

When the degree of vacuum has diminished by still another quantity E , the rod 48 will again put the motor into operation.

There will consequently exist a permanent vacuum comprised between:

$$\frac{P}{S_n} + E \text{ and } \frac{P}{S_n} - E$$

In the expansion regulating device one of the faces of the diaphragm 11 actuates a system of levers adapted to oscillate about a pivot 21. The other face of the diaphragm is in communication with the steam pipe and actuates a system of valves 62—63 the object of which is to control the expansion of the steam coming from pipe A and entering the feeding pipe B of the plant.

The weight 31 is adapted to be displaced along the lever 26.

If the system is equilibrated and if the pressure at B is of one atmosphere, the difference between the pressure on the diaphragm 11 and the pressure on the depression produced by the vacuum pump in the vacuum regulating device will be equal to

$\frac{P}{S_n}$

If $p=12$ kgr. and if $S_n=80 \text{ cm}^2$.

5
$$\frac{P}{S_n} = \frac{12}{80} = 0.150 \text{ kgr.} = 1500 \text{ kgr./M}^2$$

This is the working pressure corresponding to a temperature of 100° C .

10 The thermometer dial is of any known type. It is constituted by a saturated vapour tension thermometer. The liquid of this thermometer may be methyl-chloride and is contained in a reservoir 58. This reservoir is placed in the room the temperature of which is to be maintained constant. The reservoir is connected to a thin tube *c* which enters the apparatus at *a* (Fig. 13) and is curved around behind the thermometer dial, the free end of the tube being connected with a tank *d* containing a system of metallic tubes of a well known type to which is fixed a rod *h*. This rod controls a lever *l* under the influence of the vapor tension. At the extremity of lever *l* is suspended an equilibrated piston *p* which, under the influence of the movement produced by the vapor tension obturates more or less the passage for the liquid under pressure which enters the apparatus through a tube *r* and is discharged therefrom through a tube *q*. The pivotal center *s* of lever *l* may be manually displaced in order to obtain the desired regulation of the fixed temperature. The tube *c* opens or closes under the influence of the variations in temperature of the room and by its movement opens or closes a small capillary-orifice valve placed in the pipe-line. The opening or closing of this small valve impedes more or less the outlet of the liquid and thereby causes a variation in the pressure on the diaphragm 53.

25 This variation in the pressure actuates a lever 59 which is fixed to the diaphragm 53 and which controls by means of the lever 40 the movement of the counterweights 31 and 38 so that a temperature of the steam corresponds to a given temperature of the room.

30 When the system is inoperative and the room is cold, the small valve is closed and all the pressure of the reservoir is exerted on the diaphragm 53, thereby moving the weights towards the pivoting points of the levers. At this point the vacuum is weak and when the system is operative, the steam has a temperature in the vicinity of 100° C .

35 When the desired temperature in the room is attained, the valve opens and allows the water to flow gradually, thereby diminishing the pressure on the diaphragm 53, and the weights 31 and 38 actuated by the balancing counterweight 46 move towards the end of the levers 26 and 33, thereby producing an increase in the vacuum and a diminution in the temperature of the steam. The weights 31 and 38 are fixed in a position corresponding to the temperature desired in the room, which temperature may be varied at will by operating a button 60 (Fig. 2) which moves the needle of the dial to the desired temperature.

40 It will be remarked that the system may also operate by dispensing with the automatic regulation of the temperature. In this case the operation is effected manually and the lever 40, extended beyond its pivoting point, may be fixed in all the desired positions as explained hereinbefore.

45 The system of relief-valve and regulator for the vacuum and for the temperature of the room which has just been described is applicable above all to large installations in which the action of

the vacuum does not extend to the boilers. The steam produced in the latter at any desired pressure is expanded into the vacuum for its utilisation.

50 In this case the vacuum pump while maintaining the absolute pressure necessary in the heating network, ensures the feeding of the boilers with condensed water.

55 In smaller installations, the vacuum produced by the pump extends to the boilers which are generally fed with condensed water directly by gravity.

60 In this case, the steam not being expanded the regulating system acts directly on the combustion for proportioning the quantity of steam necessary for heating.

65 The apparatus shown in Figure 3 comprises the same references as that shown in Figure 2 (76 denoting an overflow pipe).

70 The relief-valve is replaced by a lever 67 pivoting on its centre 68. This lever is controlled by a rod 69 pivoted to the end of the slotted lever 26.

75 To the opposite ends of the lever 67 are secured flexible cables 70 and 71, passing respectively over guide pulleys 72 and 73, the cable 70 being secured at its free end to the damper door 75 disposed in the chimney and adapted to control the draught, while the free end of cable 71 is secured to the door 74 below the fire-box for controlling the admission of air for combustion. It will thus be seen that as the lever 67 swings on its pivot in one direction, the door 64 is lifted from its closed position while the door 75 gravitates toward its closing position, thereby increasing the draught through the combustion chamber, and when the lever swings in the opposite direction, the said doors 74 and 75 will also be operated in the direction opposite from that above described thereby reducing the draft through the combustion chamber.

80 The combustion is thus synchronised with the vacuum regulator in the same way and in the same conditions as in the apparatus already described in Figure 2.

85 In many cases the regulator for the temperature of the rooms is dispensed with. The control of the regulation of the temperature of the steam is effected directly by hand, the lever 40 being fixed in the desired position for obtaining that temperature.

90 As already stated, the cocks or valves and drain-cocks utilised in the system according to the invention have special features which are directly related with the system according to the invention.

95 The cock or valve shown in Figure 4 comprises a body 76, a connecting piece 77 by which it is fixed to the radiator and a head 78 which is fixed to the body 76 by a screwthread 79.

100 The head 78 which is readily accessible comprises a rod 80 of small diameter carrying in its extension a part 81 of greater diameter.

105 These two cylindrical parts are connected together by a conical part 82 carefully ground to the head 78 in an appropriate recess.

110 The rod 80 extended to the outside is provided with a handle 83 or operating hand-wheel permanently fixed to the rod, or a notched system 84 (Figure 6) intended to be operated by a detachable handle or key 85 (Figure 7).

115 A spring 86 placed in a cylindrical recess of the head 78 exerts its pressure between the operating handle or ring fixed to the rod and the bottom of the cylindrical recess of the head so that, under the influence of this pressure, the ground

surfaces of the conical part of the rod are always in good intimate contact.

Within the interior of the cylindrical part 81, an appropriate screwthread receives a needle 87 shown separately in Figure 8.

This needle comprises in a single block a first cylindrical part A of dimensions variable according to the resistance of passage to be obtained, a second part B of square section and the part 10 C screwthreaded in accordance with the internal screwthreads of the cylinder 81.

The parts A and B of the needle valve 87 are connected by a cylindrical part D forming the seat of the valve.

15 The unit formed by the cylinder 81 and the needle 87 is placed in the interior of a part 88 permanently screwed on the head 78 and having an internal form appropriate for housing the cylinder 81 and the square part of the needle and 20 cylindrical part of the seat.

It will be readily appreciated that operation of the handle 83 or 85 to impart rotation to the rod 80 moves the needle for opening or closing the valve and by this simple operation increases or 25 diminishes the quantity of steam admitted into the radiator.

When the valve is entirely opened and it is desired to adjust the installation for limiting the flow of steam and producing the useful resistance 30 it is merely necessary to employ a needle valve, the diameter A of which is more or less considerable.

Due to this fact, when the adjustment of an installation is concluded and the heads 78 have 35 been well-locked, the system absolutely cannot get out of order.

The ground conical joint device ensures permanent fluid-tightness of the system without limitation of its life and without any upkeep.

40 In these conditions, taking into consideration that the line resistance and the local resistances can never be established in a very exact manner, it will be understood that there can exist differences from one circuit to another, which makes it 45 necessary to have an adjustable resistance, more particularly the valve, whereby it is possible to have a total resistance equal for each circuit.

As will be understood, the valve described is constructed so that it is easy to cause this resistance to vary more or less, so that the adjusting device once fixed can only be altered by a special workman having the necessary tools for doing this work.

Figure 9 shows the drain-cock for the condensed water, which ensures the resistance R3 and forms an insurmountable obstacle to the passage of the steam.

It comprises a body 89 provided with two connecting pieces 90 and 91 for the inlet and outlet 60 of the condensed water.

The body 89 forms a steam cut-off device which always contains a certain quantity of water.

In each branch of this siphon is immersed a cylindrical rod 92 provided in its lower portion 65 with a certain number of circular fins 93, in the example shown seven, forming six successive expansion chambers 94. The connecting pieces are made of a very definite diameter, i. e., of a diameter 70 which depends on the quantity of water which circulates in the whole system, this quantity being in relation with an initial pressure which is a function of the quantity of condensed water to be expelled. The fins are ground so as to leave 75 only an annular passage of small size relatively

to the passage in the chamber formed by two consecutive fins.

One of the connecting pieces, as for instance the piece 90, of the siphon is connected to a reservoir of water under a head, the level of the water being maintained 200 mm. above the axis of the said connecting piece. It is only necessary to measure the water which flows freely through the other connecting piece, care being taken to maintain the level of the water of the reservoir constant at 200 mm., to determine the drainage capacity of the apparatus, since the quantity of water which flows this head of 200 mm. represents such drainage capacity.

For example, a radiator giving 21,000 calories 15 at 100° C. should discharge per second

$$\frac{21,000}{535 \times 3,600} = 10,903 \text{ cubic millimetres}$$

If the dimension of the fins is designed to only 20 allow this quantity to pass per second, the apparatus may be mounted on a radiator of 21,000 calories. In other words, the draining devices have for their object to furnish a certain quantity 25 of water under a given pressure. Generally, the apparatus is designed to furnish that quantity of water under a load corresponding to a height of 20 cm. of water, i. e., 20 gr. The draining device is consequently calibrated so as to permit its working with that load. But to vary the output, it 30 is necessary to modify the space separating the external diameter of the fins from the diameter of the chamber in which they are located.

The apparatus thus adjusted will give a resistance of 200 kilograms at 21,000 calories.

At 60° C., the discharge will only be

$$\frac{6,000}{535 \times 3,600} = 3,115 \text{ cubic millimetres}$$

and the resistance to flow will have 73 kilograms 40 as a maximum in order to follow the variations in the losses in head $R1+R2+R3$.

Since, however, actually the resistance to the flow of the water alone is only 16 kilograms, the first fins of the branch of the siphon are immersed 45 in the steam or expanded air to the level at which the resistance of passage has increased by 57 kilograms which added to 16 gives the 73 kilograms of useful resistance.

The foregoing figures are only given to explain 50 concretely the operation of the drain-cock or steam trap but instead of 200 kilograms of resistance at the start, any other greater or smaller value may be employed without modifying the result, except that in this case merely the diameter 55 of the fins would be greater or smaller.

A feature of this type of steam trap is that if the steam under the influence of a sudden pressure drives out the air and fills the apparatus, it is stopped at the end of the third or fourth fin and 60 an effective pressure of 5000 kilograms does not allow it to reach the bottom of the siphon. In other words, when the draining device has been calibrated for a well determined output of water, for instance 12 kgr. in one hour, even if the draining device furnishes only 500 gr. of water instead 65 of 12 kgr., the said steam will not pass even under a pressure which is more than 20 times the normal pressure.

This drain-cock or steam trap which ensures 70 under a very low pressure a regular discharge of the air and water forms an insurmountable obstacle to the passage of the steam.

The drain-cock thus constructed is sufficient to 75 separate the radiators from the return line.

Figure 10 shows a valve of the type shown in Figure 4 and constituting a combined valve and steam trap.

It is intended to be used on radiators fed with 5 a single pipe as shown in Figure 11. It is fixed on one side at a certain height of the radiator and on the other it is connected to a special air pipeline leading to the vacuum pump (at 95).

Between the valve and the vacuum line is inserted a fin-resistance shown in Figure 12.

This resistance which is introduced into the valve through the plug 96 is provided on each end with a blind hole 97 and a second hole 98 perpendicular to the latter and opening into the 15 first chamber.

The detachable needle of this valve is of fixed dimensions and cannot be altered, the resistance which is opposed to the passage of the air being indifferent to the normal operation of the system. 20

The object of this valve is, when it is closed, to prevent the radiator from being cleared of the air which it contains and due to that fact, the heating apparatus which cannot be fed with 25 steam, remains constantly cold. When it is opened, the steam takes the place of the air discharged by the pump.

When the steam reaches the valves and arrives at the fin-resistance, the latter opposes an insurmountable obstruction to its passage, irrespective of the difference of absolute pressure between the interior of the radiator and the vacuum line.

The steam which passes the first fins forms in fact a stopper for the steam which comes afterwards.

If during the operation of the radiator the valve is closed, the heating apparatus is progressively cooled and after a certain lapse of time which varies with the heating surface becomes 40 completely cold.

Nevertheless, it is important to point out that during the operation of the radiator, the air which is discharged automatically is saturated with water vapour which condenses in the interior 45 of the vacuum line. This quantity is, however, negligible. In the case of the valve according to Figure 10, therefore, the steam trap device merely serves to discharge air and has no function concerning the discharge of the water.

50 I claim:

1. A vacuum heating system comprising in combination, a steam producing apparatus including a manifold and a distribution system and return conduits, a vacuum producing device in communication with the entire distribution system, a vacuum regulator including a chest secured to said manifold and containing a flexible diaphragm, the space in said chest at one side of said diaphragm being in communication with the 55 vacuum producing means whereby the diaphragm will be actuated in response to variations in the degree of vacuum, a steam expansion regulator comprising a chest having a flexible diaphragm exposed at one side thereof to the steam supply 60 at the outlet of the expansion regulator, pivoted levers connected respectively to said diaphragms in such manner as to weight the diaphragms on the side thereof opposite to the side in communication with the vacuum producing means and the steam supply respectively, counterweights carried by said levers and slidable thereon to vary the leverage effect on said diaphragms, means for moving the vacuum-control weight simultaneously 65 with but at a lesser rate than the steam-control

weight, and thermostatic means for actuating said last means.

2. A vacuum heating system comprising in combination, a steam producing apparatus including a manifold and a distribution system and return 5 conduits, a vacuum producing device in communication with the entire distribution system, a vacuum regulator including a chest secured to said manifold and containing a flexible diaphragm, the space in said chest at one side of 10 said diaphragm being in communication with the vacuum producing means whereby the diaphragm will be actuated in response to variations in the degree of vacuum, a steam expansion regulator comprising a chest having a flexible diaphragm 15 therein, a pair of pivoted levers linked respectively to said flexible diaphragms so as to weight the diaphragms at the sides thereof opposite to their connection with the vacuum producing means and steam supply respectively, each of 20 said levers having a longitudinally extending slot, a counterweight suspended from the slot of each of said levers and movable from end to end of said slot, and means interconnecting said counterweights simultaneously but at different rates 25 whereby the difference in absolute pressures on the diaphragms corresponds to the losses in head due to the flow of steam in the distribution system, and thermostatic means for actuating said interconnecting means in response to variations 30 in temperature.

3. A vacuum heating system comprising in combination, a steam-supplying system including distribution pipes and return conduits, vacuum-producing means in communication with said system, vacuum regulating means and steam-expansion regulating means in communication respectively with the vacuum-producing means and steam-supplying system, pivoted levers connected respectively to said vacuum and steam-expansion 40 regulating means, weights slidable on said levers for varying the leverage thereof, means interconnecting said weights for moving them simultaneously but at different rates thereby to progressively bias said regulating means, and 45 thermostatic means automatically operative to actuate said interconnecting means thereby to maintain differences of pressure proportional to the heating effect produced by said steam-supplying system.

4. A vacuum heating system comprising in combination, a steam-supplying system including distribution pipes and return conduits, vacuum-producing means in communication with said system, a vacuum regulator and a steam-expansion 55 regulator, each of said regulators including a flexible diaphragm in communication respectively with the vacuum-producing means and the steam-supplying system, means actuated by said diaphragms for controlling the vacuum production and steam expansion, pivoted levers connected respectively with said diaphragms for weighting them at the sides thereof opposite to the sides in communication with the vacuum producing means and the steam supply respectively, 60 means movable on said levers for varying the leverage thereof, means interconnecting said movable means for moving them simultaneously but at different rates thereby to progressively bias said regulating means, and thermostatic means 65 for actuating said interconnecting means thereby to maintain differences of pressure proportional to the heating effect produced by said steam-supplying system.

5. A vacuum heating system comprising in com- 75

bination, a steam-supplying system including distribution pipes and return conduits, vacuum-producing means in communication with said system, a vacuum regulator and a steam-expansion regulator, each of said regulators including a flexible diaphragm in communication respectively with the vacuum-producing means and the steam-supplying system, means actuated by said diaphragms for controlling the vacuum production and steam expansion, a pivoted lever connected to each of said diaphragms for weighting the diaphragms at the sides thereof opposite to the sides in communication with the vacuum producing means and steam supply respectively, each of said levers having an elongated slot extending longitudinally thereof and a counterweight suspended from said slot and movable from end to end thereof, means interconnecting said weights for moving them simultaneously but at different rates along their respective slots thereby to vary the leverage of said slotted levers and the consequent weighting of their associated diaphragms, a third flexible diaphragm connected with said interconnecting levers for oscillating the same, means for normally maintaining said third diaphragm at a predetermined position, and thermostatic means effective to control said diaphragm-maintaining means.

6. A vacuum heating system comprising in combination, a steam-supplying system including distribution pipes and return conduits, vacuum-producing means in communication with said system, a vacuum regulator and a steam-expansion regulator, each of said regulators including a flexible diaphragm in communication respectively with the vacuum-producing means and the steam-supplying system, means actuated by said diaphragms for controlling the vacuum production and steam expansion, a pivoted lever connected to each of said diaphragms for weighting the diaphragms at the sides thereof opposite to the sides in communication with vacuum producing means and steam supply respectively, each of said levers having an elongated slot extending longitudinally thereof and a counterweight suspended from said

slot and movable from end to end thereof, pivoted levers interconnecting said weights for moving them simultaneously but at different rates along their respective slots thereby to vary the leverage of said slotted levers and the consequent weighting of their associated diaphragms, a third flexible diaphragm connected with said interconnecting levers for oscillating the same, means for normally maintaining said third diaphragm at a predetermined position, and thermostatic means effective to control said diaphragm-maintaining means.

7. A vacuum heating system comprising in combination, a steam-supplying system including distribution pipes and return conduits, vacuum-producing means in communication with said system, a vacuum regulator and a steam-expansion regulator, each of said regulators including a flexible diaphragm in communication respectively with the vacuum-producing means and the steam-supplying system, means actuated by said diaphragms for controlling the vacuum production and steam expansion, a pivoted lever connected to each of said diaphragms for weighting the diaphragms at the sides thereof opposite to the sides in communication with the vacuum producing means and steam supply respectively, each of said levers having an elongated slot extending longitudinally thereof and a counterweight suspended from said slot and movable from end to end thereof, pivoted levers interconnecting said weights for moving them simultaneously but at different rates along their respective slots thereby to vary the leverage of said slotted levers and the consequent weighting of their associated diaphragms, a third flexible diaphragm connected with said interconnecting levers for oscillating the same, means for supplying liquid pressure to said third diaphragm thereby to set the same to maintain said interconnecting levers at a predetermined position, and means for reducing said liquid pressure.

JEAN LAVERGNE.
